UNITED STATES PATENT OFFICE.

FORTUNE WASHINGTON, OF COLCHESTER, ILLINOIS, ASSIGNOR OF ONE-HALF TO AMBROSE CUBA, OF SAME PLACE.

KITCHEN-CABINET.

SPECIFICATION forming part of Letters Patent No. 591,440, dated October 12, 1897.

Application filed April 22, 1897. Serial No. 633,282. (No model.)

To all whom it may concern:

Be it known that I, FORTUNE WASHINGTON, a citizen of the United States, residing at Colchester, in the county of McDonough 5 and State of Illinois, have invented a new and useful Kitchen-Cabinet, of which the following is a specification.

This invention relates to kitchen-cabinets, its object being to provide a simple, cheap, 10 and efficient device of this character which will contain in one piece several of the accessories of a kitchen.

The invention consists in the several details of construction, combination, and arrangement of the several parts hereinafter fully described, and particularly pointed out in the claims.

In the drawings, Figure 1 is a perspective view looking at one side and end of the cabinet. Fig. 2 is a similar view looking at the opposite side and end of the cabinet. Fig. 3 is a vertical longitudinal section. Fig. 4 is a vertical transverse section.

Similar reference-numerals indicate similar 25 parts of the several figures.

The cabinet is indicated by 1, and is provided on one side with a cupboard 2, suitable for the reception of dishes, &c., a cupboard 3, suitable for the reception of table-linen, and 30 a drawer 4 for the reception of knives, forks, spoons, &c. The cupboard 2 extends entirely across the cabinet, but the cupboard 3 and drawer 4 extend only about half-way across.

The upper part of the cabinet is provided 35 with two horizontal dividing-walls arranged below its top 5 and indicated by 6 and 7, respectively. Two chambers 8 and 9 are thus formed, the first between the top 5 and the wall 6 and the other between the two walls 40 6 and 7. In the upper chamber 8 are two guide-rails 10, between which the ironing-board 11 is guided. This ironing-board is provided with a transverse strip 12 at its rear end, which rests upon the dividing-wall 6, and 45 the cabinet is provided with a recess 13, through which the ironing-board slides. Lugs 14, substantially equal in thickness to the strip 12, are secured on the dividing-wall 6 and are adapted to be engaged by the strip 50 12 to prevent the board 11 being entirely withdrawn. The recess 13 is closed with a

hinged lid 15 when the ironing-board is within the cabinet. The ironing-board is provided with a finger-piece 16 to facilitate its withdrawal from the cabinet. A chamber 17 is 55 formed in the lower portion of the cabinet, in which the lower horizontal guide-arm 18 of a vertical support 19 slides, while its upper guide-arm 20 slides in a guideway 21, secured to the under face of the wall 7 in the cupboard 2. The upper end of the support 19 is formed with a short pin or stud 22, adapted to fit into a recess 23 in the under face of the ironing-board when the latter is withdrawn. The ironing-board is thus firmly supported 60 and held against lateral movement when in use.

24 indicates a rod adapted to slide in ways 25 in the chamber 8 and out through an opening 26 in the end wall of the cabinet. A stop 70 27 is provided at the end of the rod to engage the end of a projection 28 on the way 25. This rod is intended to support a dish-cloth or towel.

29 indicates a clothes-rack on which to hang 75 clothes after being ironed. It consists of a series of parallel bars 30, sliding in ways 31 in the chamber 9 and through openings 32 in the end of the cabinet. The bars 30 are connected at their outer ends by a cross-bar 33, 80 34, from the lower ends of which the guide-arms 35 extend and slide in ways 36 in the chamber 17. The lower ends of the standards are connected by a cross-bar 37, and a 85 firm support is thus afforded for the outer end of the clothes-rack.

38 represents a chamber formed in the cabinet immediately back of the cupboard 3 and drawer 4. This chamber is intended to receive a churn 39 and is provided with transverse bars 40, 41, 42, and 43 intermediate its upper and lower ends. To the bars 40 and 41 are firmly secured bearings 44 for the vertical shaft 45, and this shaft is designed to 90 couple, at its lower end, to the upper end of the shaft 46 of the churn-dasher 47. The bars 42 and 43 support bearings 48, in which the horizontal shaft 49 is journaled. The adjacent ends of the shafts 45 and 49 carry 95 beveled gears 50, which mesh with each other and transmit rotary movement from the shaft 100

49 to the shaft 45. The shaft 49 projects beyond the outer face of the cabinet and is adapted to receive the crank-handle 50^a, which may be removably attached thereto. 5 The lower part of the front opening of the chamber 38 is closed by a hinged door 51 and the upper portion by a shutter 52, adapted to rest upon the upper end of the door 51 and provided with openings 53 and 54, the latter 10 admitting the passage of the shaft 49 and the other two openings receiving pins 55, which project outwardly from the bar 43. The shutter and door, respectively, are movable independently and are locked in closed position 15 by buttons 56 and 57. The shutter is provided with two buttons 58 to afford finger-holds when it is necessary to remove it to gain access to the upper portion of the chamber.

When it is desired to churn, the churn is 20 placed in the chamber 38 and the vertical shaft 45 is coupled to the shaft of the churn-dasher, after which the front opening of the chamber is closed by the shutter 52 and door 51, and the crank-handle 50^a is secured on the 25 shaft 49, and the parts are then ready for the churning to proceed.

It will be understood that changes in the form, proportion, and minor details of construction may be resorted to without departing 30 from the spirit or sacrificing any of the advantages of this invention.

What I claim is—

1. A kitchen-cabinet provided with a chamber having an open front and adapted 35 to receive a churn, transverse bars supported within the chamber intermediate its upper and lower ends, bearings on said bars, a vertical shaft and a horizontal shaft journaled in the respective bearings and provided with 40 meshing bevel-gears, the vertical shaft being adapted to be detachably connected to the shaft of the churn-dasher, and the horizontal shaft extending through the open front of the chamber, pins on one of said bars pro-

jecting through the open front of the chamber, a hinged door to close the front opening below the transverse bars, a shutter to close the remainder of said front opening, said shutter having openings for the reception of the horizontal shaft and the said pins, devices to lock the shutter and the door in their closed positions, and a crank-handle removably connected to the outer end of the horizontal shaft, substantially as described. 45

2. A kitchen-cabinet provided with a 55 chamber at its upper end, ways in said chamber, an ironing-board adapted to slide between said ways in the chamber and through an opening in the wall of the cabinet, said board being provided with a recess in its lower face, 60 a standard provided with laterally-projecting guide-arms, said arms sliding in ways within the cabinet, and a lug or pin on the upper end of the standard adapted to fit in the said recess in the ironing-board, substantially as 65 described.

3. A kitchen-cabinet provided with chambers at its upper and lower end, a clothes-rack consisting of a series of parallel bars supported within the upper chamber and 70 adapted to slide through openings in the wall of the cabinet, a cross-bar connecting the outer ends of said parallel bars, spaced standards connected at their upper ends to the said cross-bar and having their lower ends connected by a cross-brace, and guide-arms projecting horizontally from the said standards through openings in the wall of the cabinet into the lower chamber, substantially as 75 described. 80

In testimony that I claim the foregoing as my own I have hereto affixed my signature in the presence of two witnesses.

FORTUNE WASIIINGTON.
